UNITED STATES PATENT OFFICE.

STANISLAW ZDANOWICZ, OF AQUEBOGUE, NEW YORK.

DESIGN FOR A COMBINATION FOUNTAIN-PEN AND PENCIL.

59,945.

Specification for Design.

Patented Dec. 6, 1921.

Application filed May 26, 1921. Serial No. 472,917. Term of patent 14 years.

To all whom it may concern:

Be it known that I, STANISLAW ZDANOWICZ, a citizen of Poland, and a resident of Aquebogue, in the county of Suffolk and State of New York, have invented a new, original, and ornamental Design for a Combination Fountain-Pen and Pencil, of which the following is a specification, reference being had to the accompanying drawings, forming part thereof.

The figure is a plan view of a combination fountain pen and pencil showing my new design.

I claim—

The ornamental design for a combination fountain pen and pencil as shown.

STANISLAW ZDANOWICZ.
